CLOSURE FOR COLLAPSIBLE TUBES

Cesare Romati and Lorenzo Lanzetti, Turin, Italy

Application May 26, 1937, Serial No. 143,793
In Italy October 7, 1936

3 Claims. (CL 221—60)

A snap-action hinged cap as largely employed as a closure for other containers would be a suitable closure for collapsible tubes adapted to receive ointments or pastes, but a closure of this kind has not been successfully introduced for tubes on account of the fact that low price is essential for collapsible tubes. Provision of the spring member required for the snap-action undoubtedly increases the cost.

10 This invention relates to a collapsible tube with a hinged snap cap closure, in which the spring member of the snap closure is formed by the pivot of the hinge.

This pivot has a certain resiliency and is mounted in such manner that the cap is apt to yield to a slight extent transversely of the pivot.

The accompanying drawing shows by way of example a construction according to the invention.

20 Figure 1 is a cross section;

Figure 2 is an elevation of the collapsible tube top and cap, the pivot of rotation being omitted.

Figure 3 is an elevation of the collapsible tube top, the cap being omitted.

25 An annular support A for the cap is fitted on the neck c of the collapsible tube C of tin, lead or similar metal (or alloy) and held thereon by the riveted edge of the upper end of the neck c.

The cap support A is made conveniently of a 30 plastic material, for instance synthetic resin. However, it can be made of the same material as the collapsible tube and be integral with the latter. The cap B is also made conveniently of a synthetic material and is provided on the inside 35 with an insert t of resilient material, for instance cork, which in the closed cap position is pressed on the edge of the neck c insuring a tight closure of the tube.

The cap B is provided with a projection P 40 which comes between the eyes m and n of the support A and is hinged to the latter by means of the pivot h. As shown in Figure 2, the bore corresponding to the diameter of the pivot h extends through the whole thickness of the eyes m and n and not through the whole thickness of the projection p on the cover B. The latter projection is formed on both sides with openings x, y, through which the pivot h is freely movable, said pivot being guided only in the middle ridge p' 45 having a bore corresponding to the diameter of the pivot.

The pivot h is made of an elastic metal, e. g. spring steel. On the side remote from the hinge

the cap B is formed with a nose b engaging in the closed position a tapered projection a on the cap support A. These two parts form together with the pivot h a snap closure. When the cap B is pushed upwardly at its free end, it moves slightly to the right, for the pivot h bends in the opening x, y in which it is freely arranged.

On depressing the cap B to its closed position, the pivot h yields slightly and permits the nose b to snap over the projection a. By its tendency to 10 resume its straight position the pivot h holds the cap in the closed position.

We wish to be understood that we do not desire to be limited to the exact details of construction shown and described, for obvious modifications will occur to a person skilled in the art.

What we claim is:

1. A collapsible tube comprising a top piece, a closure cap of rigid material, releasable fastening projections on said top piece and cap, a pivot of 20 resilient material by means of which the cap is hinged to said top piece and the projections are held in fastened position, the cap being slightly displaceable perpendicularly to the hinge axis against the tension of the pivot the resiliency of 25 which is sufficient to permit swinging of the cap in and out of the released position without deformation of the cap.

2. A collapsible tube comprising a neck, a top piece fixed on said neck by means of the riveted 30 neck-edge, a closure cap of rigid material, releasable fastening projections on said top piece and cap, a pivot of resilient material by means of which the cap is hinged to said top piece and the projections are held in fastened position, the 35 cap being slightly displaceable perpendicularly to the hinge axis against the tension of the pivot the resiliency of which is sufficient to permit swinging of the cap in and out of the released position without deformation of the cap.

3. A collapsible tube comprising a top piece, a closure cap, releasable fastening projections on said top piece and cap, a pivot of resilient material by means of which the cap is hinged to said top piece and the projections are held in 45 fastened position, said resilient pivot being mounted in part freely in said hinged members for permitting slight displacements of the cap perpendicularly to the hinge axis for swinging the cap in and out of released position.
